UNITED STATES PATENT OFFICE.

DANIEL C. CAHALANE, OF NEW YORK, N. Y.

DESIGN FOR A COMBINED PIN-TRAY AND PEN-RACK.

41,234.

Specification for Design.

Patented Mar. 14, 1911.

Application filed January 5, 1911. Serial No. 601,048. Term of patent 7 years.

To all whom it may concern:

Be it known that I, DANIEL C. CAHALANE, a citizen of the United States, residing at New York city, in the county of New York and State of New York, have invented a new, original, and ornamental Design for a Combined Pin-Tray and Pen-Rack, of which the following is a specification, reference being had to the accompanying drawings, forming part thereof.

Figure 1 is a plan view and discloses the ornamental design which is formed in the bottom of the tray, the scalloped edges serving as a pen rack. The tray is divided by a central partition to form a pocket on each side thereof and all of the interior surfaces are curved, so that pins or other small articles may be easily slipped from the pockets. Fig. 2 is an end view of the tray disclosed in Fig. 1.

I claim:

The ornamental design for a combined pin tray and pen rack, as shown and described.

DANIEL C. CAHALANE.
